The ornamental design for a hybrid pressure and flow gauge faceplate, as shown and described.

DESCRIPTION

FIG. 1 is a front perspective view of a hybrid pressure and flow gauge faceplate in accordance with the present disclosure;

FIG. 2 is a front perspective view of the hybrid pressure and flow gauge faceplate of FIG. 1 installed within a gauge housing;

FIG. 3 is a front view of the hybrid pressure and flow gauge faceplate of FIG. 1;

FIG. 4 is a back view of the hybrid pressure and flow gauge faceplate of FIG. 1;

FIG. 5 is a top view of the hybrid pressure and flow gauge faceplate of FIG. 1;

FIG. 6 is a bottom view of the hybrid pressure and flow gauge faceplate of FIG. 1;

FIG. 7 is a first side view of the hybrid pressure and flow gauge faceplate of FIG. 1;

FIG. 8 is a second side view of the hybrid pressure and flow gauge faceplate of FIG. 1;

FIG. 9 is a front perspective view of another hybrid pressure and flow gauge faceplate in accordance with the present disclosure;

FIG. 10 is a front perspective view of the hybrid pressure and flow gauge faceplate of FIG. 9 installed within a gauge housing;

FIG. 11 is a front view of the hybrid pressure and flow gauge faceplate of FIG. 9;

FIG. 12 is a back view of the hybrid pressure and flow gauge faceplate of FIG. 9;

FIG. 13 is a top view of the hybrid pressure and flow gauge faceplate of FIG. 9;

FIG. 14 is a bottom view of the hybrid pressure and flow gauge faceplate of FIG. 9;

FIG. 15 is a first side view of the hybrid pressure and flow gauge faceplate of FIG. 9; and,
